Patented July 4, 1972

224,115

CONTROL STATION FOR PNEUMATIC TUBE SYSTEM

Herbert Kalendar, Hallandale, Fla., assignor to Advance
Metal Products, Inc., Miami, Fla.

Filed Sept. 10, 1970, Ser. No. 24,910

Term of patent 14 years

Int. Cl. D13—03

U.S. Cl. D26—13

FIG. 1 is a perspective front view of a control station for pneumatic tube system, showing my new design.

FIG. 2 is a side elevation thereof, the side opposite being similar in appearance.

FIG. 3 is a top and bottom plan view thereof.

The rear side thereof is plain.

I claim:

The ornamental design for a control station for pneumatic tube system, as shown and described.
